UNITED STATES PATENT OFFICE.

JOHN E. EDSTEDT, OF MINNEAPOLIS, MINNESOTA, ASSIGNOR TO UNIVERSAL MANUFACTURING COMPANY, OF MINNEAPOLIS, MINNESOTA, A CORPORATION OF MINNESOTA.

SELF-ADJUSTABLE SLEEVE-VALVE.

1,199,879.

Specification of Letters Patent.

Patented Oct. 3, 1916.

Application filed November 8, 1915. Serial No. 60,253.

To all whom it may concern:

Be it known that I, JOHN E. EDSTEDT, a citizen of the United States, residing at Minneapolis, in the county of Hennepin 5 and State of Minnesota, have invented certain new and useful Improvements in Self-Adjustable Sleeve-Valves; and I do hereby declare the following to be a full, clear, and exact description of the invention, such as 10 will enable others skilled in the art to which it appertains to make and use the same.

My invention has for its object to provide an expansible valve of the piston type, whereby play, due to wear, may be taken up 15 and the valve therefore kept in prime operative condition for indefinitely, or for a very great length of time.

Generally stated, the invention consists of the novel construction and arrangement 20 of parts hereinafter described and defined in the claims.

In the accompanying drawings which illustrate the invention, the valve is shown as incorporated in an internal combustion 25 engine of a type disclosed and claimed in Letters Patent of the United States No. 1,161,184 and granted to Oscar M. Bergstrom, of date November 23rd, 1915, but it will be understood that the said valve is 30 capable of general application wherever an expansible valve or similar device is required.

In the accompanying drawings which illustrate the invention, like characters 35 indicate like parts throughout the several views.

Referring to the drawings: Figure 1 is a vertical section showing the cylinder, piston and one of the valves of the engine, some 40 parts being broken away; Fig. 2 is a side elevation of the valve showing the same removed from the engine; Fig. 3 is a plan or upper end view of the valve; Fig. 4 is a vertical section taken through the valve on the line $x^4 x^4$ of Fig. 2; and Fig. 5 is a horizontal section taken on the line $x^5 x^5$ of Fig. 4.

Of the parts of the engine, the numeral 1 indicates the cylinder, the numeral 2 the 45 piston, the numeral 3 the connecting rod, the numeral 4 the cylindrical valve seat connected to the upper end of the cylinder by a port 5, the numeral 6 the sleeve-like piston valve, and the numeral 7, the rod for reciprocating the said valve, which latter is pivot-

ed to the lower end of the said valve below a horizontal partition thereof. In this arrangement, it is only the upper end portion of the valve that is subjected to great heat, it being assumed that the said valve, in this 60 instance is the exhaust valve of the engine. On its side which is away from the port 5, the valve has a longitudinal slit 9 that extends from a point immediately above its horizontal partition 8, to the extreme upper 65 end of the said valve. This slit makes the valve slightly, but sufficiently expansible to take up wear. Below its upper end, the said valve is provided with a conical internal flange 10 that is also split at one point by 70 the slit 9. This conical flange 10 is engaged by the conical head of an expander 11, which expander is also formed with a depending sleeve-like portion 12 of decreased diameter, terminating at its lower end in a 75 perforated head through which is passed a stud or rigid stem 13, the lower end of 80 which is screwed into the horizontal partition 8 of the valve. The upper end of the stem 13 is threaded and is provided with a nut 14. A coiled spring 15 surrounds the stem 13 and is compressed between the nut 14 and the lower end of the sleeve 12, and hence, exerts a force which not only keeps the conical expanded head 11 in tight engagement with the conical flange 10, but 85 exerts sufficient force to automatically take up any play which may be caused by wear between the valve and its seat. In this way, the valve will be automatically expanded 90 and will always be kept in close engagement with its seat, thereby avoiding leakage.

The port 5 will have considerable circumferential or lateral extension, but the slit in the valve is located on the far side thereof, 95 and far beyond the extremities of the said port 5. All that portion of the valve therefore, which moves over the port 5, will be kept in close engagement with its seat. The exhaust will be through the port 5 and over 100 the upper end of the valve, and thence, out through the upper extremity of the valve seat 4, so that the upper portion of the valve will be subject to the greatest expansion, and hence, to the greatest wear. To protect 105 the spring 15 from the heat due to the exhaust, a light metal cap 16 is inserted into the upper end of the valve, against a stop shoulder at 17, and this cap is detachably held in position by an expansible split 110

spring ring 18 that is sprung into an internal groove formed in the extreme upper end portion of the said valve.

By reference particularly to Fig. 5, it will be noted that the conical head 11, has a plurality, as shown, 4 tapered surfaces at 11^a which, alone, engage the conical surface of the internal flange 10 of the valve. I have found that this limited contact gives better results than a complete circular contact, in that it is an easier matter for the spring to move the expander and automatically take up the play, due to wear, between the valve and valve seat.

15. What I claim is:

1. The combination with a circumferentially expansible piston-like valve or member, of a yieldingly pressed expander within said valve having tapered engagement therewith and exerting a yielding force tending to expand the same.

2. The combination with a hollow piston-like valve slit to make the same circumferentially expansible, of an expander within said valve having tapered engagement therewith, and a spring connection between said valve and expander exerting a force tending to expand said valve.

3. The combination with a hollow piston-like valve slit to make the same circumferentially expansible, of an expander within said valve having tapered engagement therewith, a spring connection between said valve and expander exerting a force tending to expand said valve, and a detachable cap applied in the end of said valve and protecting the said spring connection from external heat.

4. The combination with a hollow piston valve having a longitudinal slit making the same expansible, and having a transverse partition in the vicinity of the inner extremity of the slit, a stem secured to said partition and extended axially within said valve, an expander having tapered engagement with the interior of said valve and provided with a sleeve surrounding said stem, a nut on said stem, and a coiled spring surrounding said stem and compressed between said nut and the end of the sleeve of said expander.

5. The combination with a hollow piston valve having a longitudinal slit making the same expansible, and having a transverse partition in the vicinity of the inner extremity of the slit, a stem secured to said partition and extended axially within said valve, an expander having tapered engagement with the interior of said valve and provided with a sleeve surrounding said stem, a nut on said stem, and a coiled spring surrounding said stem and compressed between said nut and the end of the sleeve of said expander, and a cap detachably applied to the slit end of said sleeve and protecting said spring and expander from the direct action of external heat.

6. In an engine, the combination with a cylinder and piston the former having a cylindrical valve seat on one side connected thereto by a port, of a hollow piston valve working in said valve seat, said valve having an internal partition and having a longitudinal slit extending approximately from said partition to the outer end of said valve, on that side of the valve which is opposite to said port, and an expander in said valve having tapered engagement therewith.

7. In an engine, the combination with a cylinder and piston the former having a cylindrical valve seat on one side connected thereto by a port, of a hollow piston valve working in said valve seat, said valve having an internal partition and having a longitudinal slit extending approximately from said partition to the outer end of said valve, on that side of the valve which is opposite to said port, and a spring pressed expander within said valve having tapered engagement therewith, and a cap detachably applied to the outer end of said valve and protecting said spring pressed expander against the direct action of the external heat.

In testimony whereof I affix my signature in presence of two witnesses.

JOHN E. EDSTEDT.
